UNITED STATES PATENT OFFICE.

HOWARD R. ROBERTS, OF CHICAGO, ILLINOIS.

COIN-CONTROLLED MECHANISM.

1,410,510.

Specification of Letters Patent. Patented Mar. 21, 1922.

Application filed February 16, 1922. Serial No. 537,003.

To all whom it may concern:

Be it known that I, HOWARD R. ROBERTS, a citizen of the United States, residing at Chicago, in the county of Cook and State of Illinois, have invented certain new and useful Improvements in Coin-Controlled Mechanism, of which the following is a specification.

My invention relates to coin controlled means, for use in connection with a combined clock and bank, while not necessarily restricted to this use.

An important object of the invention is to provide means of the above mentioned character, whereby a coin must be fed into the coin shoot, before the clock may be wound, the construction being such that coins of different sizes or denominations may be employed to permit of the winding of the clock.

20 A further object of the invention is to provide means of the above mentioned character, which are extremely simple in construction, cheap to manufacture and reliable in operation.

25 A further object of the invention is to provide a device of the above mentioned character, which may be applied to a clock of the ordinary construction, without materially altering its construction.

30 Other objects and advantages of the invention will be apparent during the course of the following description.

In the accompanying drawings forming a part of this specification, and in which like numerals are employed to designate like parts throughout the same,

Fig. 1 is an elevation of the front side of a clock embodying my invention,

40 Fig. 2 is a similar view of the rear side of the clock,

Fig. 3 is a similar view with the rear plate or cover removed,

Fig. 4 is a detail section taken on line 4—4 of Fig. 2, showing the coin slot,

45 Fig. 5 is a fragmentary elevation of the inner side of the rear plate or cover, showing the reciprocatory coin pusher,

Fig. 6 is a transverse section taken on line 6—6 of Fig. 5, and,

50 Fig. 7 is a transverse section taken on line 7—7 of Fig. 2.

In the drawings, wherein for the purpose of illustration is shown a preferred embodiment of my invention, the numeral 10 des-

ignates the casing of a clock, shown as a 55 desk clock, while the invention is in no sense restricted to this particular form of clock. The upper portion of the casing receives and holds the clock works, including a frame plate 11. The numeral 12 designates the dial 60 and 13 the hands of the clock. The lower portion of the casing is in the form of a coin receiving and holding chamber 14.

The rear side or back of the casing is open, and is adapted to be covered by a plate 65 or cover 15, which is slid upwardly between a flange 16, and brackets 17, spaced from these flanges. The plate or cover 15 is held against downward movement by a bottom 18, which is locked to the casing 10 by any 70 suitable means. When the bottom 18 is removed from the casing, the plate or cover 15 may then be removed therefrom, by a downward movement with relation thereto.

The numeral 18 designates a ratchet 75 wheel, which is suitably mounted upon the winding shaft or stem of a clock works. Where the invention is applied to the ordinary clock, the key carried by the winding shaft is removed and the ratchet wheel 18 80 substituted therefor. The ratchet wheel 18 must be turned in the direction of its arrow, to wind the clock. The ratchet wheel 18 is provided with a slotted hub 19, arranged beneath an opening 20, in the plate 85 15, as shown in Fig. 2. A suitable key may be inserted through the opening 20 and engaged with the slotted hub 19 to turn the ratchet wheel.

The numeral 21 designates an approximately vertically arranged arm or lever, pivoted at 22, upon the frame plate 11. The upper end of this lever is bent laterally into a dog or pawl 23, held in engagement with the ratchet wheel 18 by a leaf spring 24, 95 secured thereto. This leaf spring is slidably mounted in an aperture formed in a stationary stud 25.

The rear plate or cover 15 is provided in its central portion with an outwardly pressed 100 hollow rib 26, preferably horizontally arranged. A reciprocatory carriage 27, curved in cross section, is slidably mounted upon the exterior of this rib, and is guided thereby. The numeral 28 designates a reciprocatory coin pusher, connected with the carriage 27 by means of a transverse stud 29, 105 slidable in a slot 30, formed in the rib 26.

The coin pusher 28 has its free end bent laterally into an extension 31, adapted to be arranged beneath and in alignment with the lower end of the arm 21, when the pusher 5 is in the starting position, and forms a continuation, in effect, of the arm 21. The coin pusher 28 is provided with an upstanding portion or arm 32, having a laterally and 10 forwardly extending flange 33. The flange 10 33 constitutes one edge wall of the coin shoot, and the lever 21 the other edge wall, while the plates 11 and 15 constitute the side walls. In other words, the coin passes 15 between the plates 11 and 15, and is supported 15 between flange 33 and the lower end of the lever 21, whereby when the coin pusher 28 is shifted to the right, the lever will be 20 swung upon its pivot, and the ratchet wheel 18 released.

20 The coin pusher 28 is provided with adjustable means to support and release the coins, the same including a reciprocatory rod or pin 34, slideable within a housing 35, and projecting through an opening 36, in 25 the coin pusher 28. The rod or pin 34 is normally retained in the outer position by a compressible coil spring 37, and the rod is pushed inwardly by a button 38 secured to its outer end. When the rod is pushed 30 inwardly, it extends across the coin shoot, and hence will support the coin between the flange 32 and the lever 21, as indicated in Fig. 5.

The coin is fed into the coin shoot through 35 an opening 39, formed in the plate 15, which opening is partly covered by a guard 40.

The coin opening 39 is of a diameter to receive a coin of the maximum diameter, such for instance as a quarter, and the coin 40 shoot, having its width defined by the flange 33 and lever 21, is sufficiently wide to receive a coin having the maximum diameter, as the quarter. This construction permits of the use of a quarter, and all coins of 45 smaller diameters, such as pennies, dimes or nickles.

To wind the clock, the carriage 27 is shifted to the left, Fig. 2, and the clock may be held in the left hand, with the thumb de- 50 pressing the button 38. The coin is now introduced into the opening 39, and will gravitate downwardly within the coin shoot, and rest upon the inner end of the rod or pin 34, now projecting inwardly beyond the plate 15. The button, while retained 55 depressed, is now shifted to the right, Fig. 2, which movement advances the carriage 27 and coin pusher 28 in the same direction. The flange 33 now engages the coin and 60 moves it into engagement with the lower end of the lever 21, whereby the dog or pawl 23 will release the ratchet wheel 18. While retaining the button 38 depressed in the shifted position, the key is employed to turn 65 the ratchet wheel 18 in the direction of its

arrow, Fig. 3, for winding the clock. After the winding action is completed, the button is released, and the spring 37 returns the rod or pin 34 to the outer position, and the coin falls into the coin chamber 14, from 70 which it may be removed by the authorized person.

It is to be understood that the form of my invention herein shown and described is to be taken as a preferred example of the same, 75 and that various changes in the shape, size, and arrangement of parts may be resorted to, without departing from the spirit of my invention, or the scope of the subjoined claims.

Having thus described my invention, I 80 claim:

1. The combination with a ratchet wheel adapted to be secured to the winding element of a clock works, of a pivoted lever 85 having a portion thereof arranged to engage the ratchet wheel, a spring to normally hold the lever in engagement with the ratchet wheel, a plate arranged upon one side of the lever, a reciprocatory coin pusher 90 carried by the plate and provided with an upstanding coin engaging element arranged opposite a portion of the lever, a reciprocatory bolt carried by the coin pushing element and adapted to be shifted inwardly 95 into the path of travel of the coin for supporting the same, and a spring to move the bolt outwardly.

2. The combination with a ratchet wheel adapted to be secured to the winding element of a clock works, of a pivoted lever 100 having a portion thereof normally engaging the ratchet wheel, a movable coin pusher arranged near the lever and carrying a coin engaging element disposed opposite the lever 105 in spaced relation, and a movable coin supporting element carried by the coin pusher and adapted to be shifted to an inner position in the path of travel of the coin to support the same.

3. The combination with a rotatable element adapted to be secured to the winding element of a clock works, of a pivoted lever adapted to engage the rotatable element, a movable coin pusher arranged near the 115 lever and having a coin engaging element arranged opposite to the lever and spaced therefrom, a movable coin supporting element carried by the coin pusher and adapted to be shifted inwardly in the path of travel 120 of the coin, and means to normally retain the coin supporting element in the outer position.

4. In coin controlled mechanism, a movable element, a coin pusher having a part 125 adapted to engage a coin and move it into engagement with the movable element, and a coin supporting element connected with the pusher to shift the pusher toward the movable element and adapted to be moved with 130

relation to the pusher at substantially a right angle to the direction of movement of the pusher.

5. In coin controlled mechanism, a movable element, a reciprocatory coin pusher having a coin engaging part to shift a coin into engagement with said element, said pusher having a transverse opening formed

therein, a coin supporting element extending through the opening and movable transversely of the pusher, and yielding means to oppose the inward movement of the coin supporting element. 10

In testimony whereof I affix my signature.

HOWARD R. ROBERTS.
